STOKER

Joseph S. Bennett, Merion, Pa., assignor, by mesne assignments, to American Engineering Company, Philadelphia, Pa., a corporation of Pennsylvania

Application July 30, 1940, Serial No. 348,397

10 Claims. (Cl. 110—44)

This invention relates to stokers, and more particularly to stokers of the multiple retort underfeed type.

One object of the present invention is to provide a generally improved stoker which is simple in construction and highly efficient in operation.

Another object is to provide in a stoker of the class described an improved dump grate construction which functions to feed the ashes through a discharge opening, the dump grate being provided with a flexible support which enables downward movement thereof to permit large clinkers to pass through the discharge openings.

Another object is to provide in a stoker of the class described a new pusher arrangement for underfeeding the fuel along the stoker.

A further object is to provide certain novel details of construction which simplify the structure of the stoker as a whole.

Other and further objects will become apparent as the description of the invention progresses.

Of the drawings:

Fig. 1 is a longitudinal sectional view taken through one of the retorts of the stoker comprising the present invention.

Fig. 2 is a side view, partly in section, of the lower end of the stoker showing the improved dump grate construction forming a part of the present invention.

Fig. 3 is a sectional view taken substantially along line 3—3 of Fig. 2.

Fig. 4 is a side view partly in section of the upper end of the stoker showing the improved ram box construction associated therewith.

Fig. 5 is an elevational view partly in section taken substantially along line 5—5 of Fig. 4.

Fig. 6 is a sectional view taken substantially along line 6—6 of Fig. 4.

Fig. 7 is a fragmentary view partly in section, showing the construction of one of the pushers provided in the retorts of the stoker.

Fig. 8 is a sectional view taken substantially along line 8—8 of Fig. 7.

Fig. 9 is a sectional view taken substantially along line 9—9 of Fig. 7.

Fig. 10 is a longitudinal sectional view taken substantially along line 10—10 of Fig. 7.

Fig. 11 is an end view taken substantially along line 11—11 of Fig. 1.

Fig. 12 is a sectional end view taken substantially along line 12—12 of Fig. 4, and

Fig. 13 is a longitudinal sectional view of a modified form of pusher construction.

Referring to the drawings, the numeral 1 des-

ignates a furnace having a stoker 2 mounted therein. Stoker 2 comprises alternately disposed retorts 3 and tuyère rows 4, and inclines downwardly and rearwardly from the front wall 5 of the furnace. Fuel from hoppers 6 is fed to the retorts 3 by rams 7 through openings 8 provided in wall 5 in the usual manner. Rams 7 may be operated by any suitable power mechanism indicated generally at 9. The bottom of each retort of the illustrated stoker has provided therein an upper pusher 10, an intermediate dead plate 11, a lower pusher 12, and an air cooled dead plate 13. A fuel supporting plate 14 forms the bottom of each opening 8 and extends into the retort directly above upper pusher 10. The pushers 10 and 12 underfeed the fuel along the retorts to extension grates 15, which in turn feed the fuel and ashes to a reciprocatory dump grate 16. From dump grate 16 the ashes are fed through a discharge passage 17 defined at the bottom thereof by the dump grates 16 and at the top by the lower portion 18 of the rear wall 19 of the furnace.

When the terms "front" and "rear" are used herein it is to be understood that the term "front" indicates the portion of an element extending toward the front wall 5, and the term "rear" relates to the portion of the element extending toward the rear wall 19.

The upper pusher 10 has secured to the forwardly disposed end thereof a bracket 20 to the upper end of which a slideable operating rod 21 is secured in any suitable manner. Rod 21 extends through an aperture provided in the plate

22 of the stoker front 23 and has pivotally connected to its outer clevis end a second rod 24. Rod 24 has mounted thereon a sleeve 25 to which is pivotally connected an actuating lever

26. Lever 26 is pivoted intermediate its ends to a fixed bracket 27 secured to and extending outwardly from the stoker front 23. The upper end of lever 26 is pivotally attached to the forwardly disposed end of feeding ram 7 while the lower end thereof is pivotally connected to a sleeve 28 mounted on a rod 29, which rod in turn is pivotally connected to a second rod 30 slidably mounted in stoker front 23. The left hand end (Fig. 1) of rod 30 is pivotally connected to a connecting

rod 31 which in turn is connected to a member 32 which extends through an enlarged aperture provided in the vertical partition member 33 disposed beneath the lower end of stoker 2. Member 32, as shown in Fig. 1, is pivotally attached to the framework 15 of extension grate 15. Up-

55

per and lower pushers 10 and 12 are connected for simultaneous operation by a rod 34.

From the foregoing description it is seen that upon operation of rams 7 by the power mechanism 9 lever 26 is caused to move about its pivotal connection on bracket 27, thereby simultaneously actuating pushers 10 and 12 and extension grate 15. The usual removable washers 35 and 36 are provided on rods 24 and 29 respectively, near the right hand ends thereof (Fig. 1) whereby the extent of movement of pushers 10 and 12 and extension grates 15 may be varied. Similar removable washers 37 may be placed on rod 34 to permit relative movement of pushers 10 and 12 and to vary such relative movement.

The right hand end of member 32 has also pivotally attached thereto the upper end of a lever 38. Lever 38 is pivoted at the lower end thereof, as shown at 38', and has pivotally mounted intermediate its ends a collar 39 slidably mounted on a rod 40 between fixed abutments 39^a and 39^b secured to rod 40. Rod 40 is pivotally connected at the left hand end thereof to an operating member 41 for the dump grates 16. Accordingly, upon actuation of lever 26 by the rams 7, as previously described, dump grates 16 will be simultaneously operated. A series of removable washers 39^c may be placed on rod 40 between collar 39 and abutment 39^b whereby the extent of movement of dump grate 16 may be varied.

Air for combustion purposes is supplied to the furnace from a plenum chamber 42 disposed beneath the stoker, which in turn receives air under pressure from any suitable fan or blower mechanism (not shown) through a passage 43.

As shown in Fig. 1, fluid conducting tubes 44 extend vertically along the inner surface of the front wall 5, and thence over the tuyère rows 4 and the portions of the extension grates 15 in alignment therewith, and then are bent downwardly and forwardly, as shown at 45, and terminate at their lower ends in a header 46 disposed beneath the lower end of the stoker. The rear wall 19 also has provided thereon fluid conducting tubes 47 which extend vertically therealong from a header 48. Fluid may be supplied to the headers 46 and 48 from a boiler (not shown) or from any other suitable source. The upper ends of tubes 44 and 47 may also terminate in said boiler or in headers, which in turn may be connected to any disposal means for the fluid.

As shown more particularly in Figs. 1 and 2, an air cooled stationary member 49 is disposed between extension grates 15 and dump grates 16.

The retorts 3 of the stoker 2 are bounded at the sides thereof by longitudinally extending plates 50 secured in any suitable manner at their upper ends to brackets 51 mounted on the I-beam 52 forming a portion of the stoker front 23. A series of tuyère supporting members 53 are secured by any suitable means, such as by bolts 54, to the upper flanges 135 of side plates 50. Supporting members 55 for ram box cap extensions 56 are also mounted on plates 50 and are secured to the flanges 135 thereof by bolts 57. These members 55 extend between the uppermost tuyère supporting members 53 and the brackets 51, and are also secured thereto by bolts 58. The upper flanged portion 59 of supporting members 55 and the top flat surface 60 of brackets 51 are in alignment, the former, as pointed out before, form the supports for the ram box

cap extension 56, while the latter form the supports for the ram box caps 62 proper.

The side plates 50 extend over the entire length of the stoker 2 and the lower ends thereof have secured thereto brackets 63 which rest upon a transverse I-beam 64, which in turn is supported upon any suitable foundation 65 disposed adjacent the ash pocket 66. Ash pocket 66, as will be observed upon reference to Fig. 1, receives the ashes fed from the stoker through discharge passage 17.

Referring more particularly to Figs. 1 and 2, it will be seen that each operating member 41 has secured to the left hand end thereof an enlarged rectangular portion 68 which extends between the lower surface of air cooled member 49 and a bearing member 69 secured in any suitable manner to the side plates 50 near the lower ends thereof. The left hand end of rectangular portion 68 is pivoted at 70 to the right hand end of dump grate 16. As shown more particularly in Fig. 3, the dump grates 16 in the present instance are made up of independently operable sections, each consisting of three interconnected members 71, 72 and 73. Member 71 consists of an upper serrated fuel and ash supporting portion 74, having a relatively short flange 75 at the left side thereof (Fig. 3) and a relatively long flange 76 at the right side thereof. Element 30 73 is similar in construction to element 71, except that it has a relatively short flange 77 provided at the right side thereof, and a relatively long flange 78 at its left side, these flanges being connected by an upper serrated fuel and ash supporting portion 79. Member 72 is generally similar in construction to members 71 and 73, except that it contains relatively long flanges 80 and 81 at both sides thereof, these flanges being connected at their upper edges by a serrated fuel and ash supporting portion 82. Flanges 76 and 80 of members 71 and 72 are secured together by a bolt 83. Flanges 81 and 78 of members 72 and 73, respectively, are likewise secured together by a bolt 84. A rod 86 extends through the lower ends of flanges 76, 80, 81 and 78, and has mounted thereon a roller 87 which is supported on the upper bearing surface 88 of a bracket 89. Rod 86 is held in position by nuts 90 provided at the opposite ends thereof.

From the foregoing description it is seen that each dump grate section 16 is made up of three relatively narrow members. Thus, in the event that damage should occur to any one or more of the members 71, 72 or 73 of a section, it is only necessary to remove the damaged member and replace it with a new one. Each section is operated by power mechanism 9 through a series of independent connections as previously described.

Brackets 89 are pivotally supported on the side plates 50 near the lower ends of the latter, as shown at 91, and each bracket has secured to the downwardly extending flanges 92, 92 thereof, by bolts 93, a pair of elongated plates 94, 94. The lower ends of plates 94, 94 are pivotally connected to the outer end of a tubular member 95. Tubular member 95 is provided with screw threads 96 at the right hand end thereof (Fig. 2) which make threaded engagement with the internal threads 97 provided at the right hand end of a sleeve member 98. Tubular member 95 and sleeve 98 extend through an enlarged aperture 99 provided in the web 100 of I-beam 64 upon which the lower end of the stoker is supported. Integral

with sleeve 98 and disposed to the right of web 100 of I-beam 64 is a spring seat 101 against which one end of a coil spring 102 abuts. The other end of coil spring 102 engages the inner surface of a block member 103 slidably mounted on sleeve 98. A pair of channel members 104 and 105 are secured to the lower flange 106 of I-beam 64 by bolts 107 or by any other suitable fastening means. The outer ends of channel members 104 and 105 are pivotally mounted on trunnions 108 and 109 extending outwardly from block 103. By this construction it is seen that in the event of an abnormal load, such as may be caused by movement of an unusually large clinker through the discharge opening 17, dump grates 16, and consequently brackets 89, will move downwardly thereby causing plates 94, 94 to actuate tubular member 95 and sleeve 98 to the right. By this action spring seat 101 will also move to the right. However, inasmuch as sliding block 103 is held against movement by channel members 104 and 105, spring 102 will be compressed and when the load has been relieved the spring will restore the parts to normal position. By providing the threaded tubular and sleeve members 95 and 98, the position of dump grates 16 may be varied so as to increase or decrease the size of the discharge passage 17. The threaded portions 96 and 97 may be lubricated by any suitable lubricating fluid supplied to the interior of tubular member 95, the fluid being retained therein by a plug 110. Apertures 111 provided in tubular member 95 permit fluid to drip into sleeve 98 and thus lubricate the threaded portions 96 and 97.

Referring more particularly to Figs. 4 to 6, it will be noted that each ram box cap 62 is provided with a substantially hollow portion 114 having at the bottom thereof an upwardly inclined portion 115 which extends from the plate 22 of the stoker front to the forwardly disposed edge 116 of ram box cap extension 56. A flange 117 extends outwardly from each side of each ram box cap 62 and rests upon the upper surface 66 of a bracket 51. Bolts 118 extending through flanges 117 and the upper surfaces of brackets 51 rigidly secure the ram box caps 62 in position.

Each ram box cap extension 56 comprises an upper hollow portion 119 having an opening 120 at each side thereof through which air discharging from outlet openings 120' provided in air boxes 121 may enter. The air so entering chamber 119 is discharged therefrom into the furnace through a series of apertures 122 provided at the rearwardly disposed end thereof. Each ram box cap extension 56 has also provided at the sides thereof depending legs 123 and 124 which rest upon the upper flanges 59 of supporting plates 55. Legs 123 and 124 have provided at the inner sides thereof a pair of enlarged longitudinally aligned apertured recesses 125 and 126. Extending vertically from each flange 59 is a second flange 127 having apertures therein in alignment with the apertures provided in the recesses 125 and 126 respectively. The lower end of each side wall 128 of the air boxes 121 is also provided with apertures in substantial alignment with the apertures in flanges 127 and legs 123 and 124 of ram box cap extension 56. Bolts 129 extending through said aligned recesses rigidly secure each ram box cap extension in position.

The portion of Fig. 5 shown in section illustrates the structure of the ram box cap extension 56 and air box 121 at the air openings 120 and 120', while the portion to the left thereof

shows the structure of the inner surface of the furnace wall adjacent the stoker. It will be noted that a series of vertically disposed grid bars 130 are provided at the furnace side of the air boxes 121. These grid bars occupy the entire inner end of each air box 121 extending between adjoining ram box cap extensions 56. The construction of the air boxes 121 and grid bars 130 is generally similar to those shown in United States Patent No. 1,907,066. Accordingly, a detailed description thereof may be had upon reference to said patent.

The ram box caps 62 and ram box cap extensions 56 also are generally similar in construction to those shown in United States Patent No. 1,907,066, except insofar as the fastening means are concerned. In the present instance bolts 129 are employed to rigidly secure the ram box cap extensions in position. Any suitable fire brick 131 is supported on the upper surfaces of the ram box caps 62, ram box cap extensions 56, and the upper surfaces of air boxes 121 to complete the front wall 5. By this construction it is seen that the ram box cap extensions may be removed without disturbing the brickwork 131. By simply removing the bolts 129 the ram box cap extension may be moved rearwardly into the furnace and a new one may then be inserted in its place.

The lower surface 119' of ram box cap extension 56 is inclined and is in substantial alignment with the surface 115 of ram box cap 6. These surfaces form the upper fuel deflecting portions of fuel inlet openings 8. Openings 8 are bounded at the sides by members 55 and brackets 51 and at the bottom by fuel supporting plates 14.

Upon reference to Fig. 12, it will be seen that the upper surface 132 of the flange 133 provided at the lower end of each supporting member 53 and 55 is constructed so as to be substantially parallel to the lower surface 134 of the flanges 135 of side plates 50. By this construction it will be noted that the head of the bolt 54, as well as the securing nut 136, will lie flush against the surfaces 132 and 134 respectively.

As shown more particularly in Figs. 4 and 12, members 53 and 55 have each provided thereon a series of substantially vertically and longitudinally extending vanes or ribs 53' and 55' respectively, which tend to maintain these members relatively cool during operation of the furnace.

Referring to Figs. 7 to 10 inclusive, it is seen that each pusher 10 is slidably mounted on the forward extension 137 of dead plate 11, and extends between the side plates 50 forming the side walls of a retort 3. Portion 137 of dead plate 11 also extends between the side plates 50, 50 and is secured thereto by a series of bolts 138.

Pushers 10 and 12 are similar in construction, and accordingly a description of one will suffice for both. As shown more particularly in Fig. 7, pusher 10 is made up of three sections, a forwardly disposed section 140, an intermediate section 141, and a rearwardly disposed section 142. Section 140 comprises an upper wall 143, a pair of side walls 144, a forwardly disposed wall 145, and a rear wall 146. Forwardly disposed wall 145 is secured to bracket 20 in any suitable manner, such as by bolts 147. Rear wall 146 is secured to the forward wall 148 of intermediate section 141 by bolts 149. Section 141 also has an upper wall 150, a portion of which, as shown at 151, inclines downwardly and rearwardly and terminates in a rearwardly disposed vertical wall 152 which in turn is secured by bolts 153 to the forward wall 154 of rear section 142. Intermediate section

also comprises a pair of side walls 155, 155 having inwardly extending flanges 156, 156 provided at the lower ends thereof. Supporting portion 137 has secured thereto a retaining and guiding member 157 for pusher 10. Guide member 157 consists of a body portion 158 extending transversely of supporting portion 137 and is secured to the latter by any suitable means, such as by bolts 159. A flange 160 extends outwardly from each end of body portion 158 to overlap the flanges 156, 156 provided at the lower ends of the side walls 155, 155 of intermediate section 141. By this construction it is seen that pusher 10 is prevented from tilting during its reciprocatory feeding movements. Rearwardly disposed section 142 comprises an upper inclined section 162 in substantial alignment with portion 151 of intermediate section 141 and terminates in a vertically disposed rear wall 163. Section 142 is also provided with side walls 164.

The outer surfaces of side walls 144 of forwardly disposed member 140 are provided with a series of vertically disposed ribs 165, as shown more particularly in Fig. 10. These ribs are provided to prevent the passage of fuel siftings between pusher 10 and the side plates 50 of the retort 3.

Fig. 13 shows a somewhat modified pusher construction 170 which may be utilized to advantage in cases where it is desirable to construct pushers of different lengths. This construction also shows a forwardly disposed section 171, an intermediate section 172, and a rearwardly disposed section 173. The forwardly disposed section 171 is bolted to a bracket 20'. By this arrangement additional intermediate or forwardly disposed sections 172 or 171 may be employed to obtain a pusher of the desired length.

While the embodiments herein shown and described are admirably adapted to fulfill the objects primarily stated, it is to be understood that the invention is not to be limited thereto, since it may be embodied in other forms, all coming within the scope of claims which follow.

What is claimed is:

1. A tuyère support adapted to be mounted upon the side plates of a stoker furnace, said tuyère support comprising a substantially rectangular body portion having a flange disposed along the lower edge thereof, a series of cooling vanes provided on one surface of said body portion, and said flange tapering inwardly from its free end whereby said flange has its greatest thickness at the outer end thereof, and diminishes in thickness as it approaches the body portion.

2. A tuyère support for stokers comprising a substantially rectangular body portion, a flange integral with said body portion and extending laterally from one edge thereof, said flange tapering from the free end towards its connection with the body portion whereby said flange is of greatest thickness at its outer end, and cooling means provided on said body portion.

3. In a device of the class described, the combination of dump grates adapted for assembly at one end of a stoker, means for pivotally supporting one end of said dump grates, means providing a resilient support for said dump grates, whereby said dump grates may move downwardly when subjected to abnormal loads, and means for reciprocating said dump grates to feed the fuel and refuse supported thereon to a place of disposal.

4. In a device of the class described, the com-

bination of dump grates adapted for assembly at one end of a stoker, means for pivotally supporting one end of said dump grates, means providing a resilient support for said dump grates, whereby said dump grates may move downwardly when subjected to abnormal loads, means for reciprocating said dump grates to feed the fuel and refuse supported thereon to a place of disposal, and a series of vertically disposed feeding faces provided at the upper portion of said dump grates.

5. In a device of the class described, the combination of dump grates adapted for assembly at one end of a stoker, means for pivotally mounting one end of said dump grates, a support for said dump grates, anti-friction means disposed between said support and said dump grates, means for reciprocating said dump grates to feed the materials supported thereon to a place of disposal, and resilient means for said support whereby said dump grates may move downwardly when subjected to excessive loads.

6. In a device of the class described, the combination of dump grates adapted for assembly at one end of a stoker, means for pivotally supporting one end of said dump grates, and means providing a resilient support for said dump grates, whereby said dump grates may move downwardly when subjected to abnormal loads, said last mentioned means comprising a pivotally mounted bracket having a supporting portion and a depending portion, and resilient means operatively connected to said depending portion.

7. In a device of the class described, the combination of dump grates adapted for assembly at one end of a stoker, means for pivotally supporting one end of said dump grates, and means providing a resilient support for said dump grates, whereby said dump grates may move downwardly when subjected to abnormal loads, said last mentioned means comprising a pivotally mounted bracket having a supporting portion and a depending portion and a movable member pivotally connected to said depending portion, a spring seat integral with said movable member, a spring mounted on said movable member, one end of said spring engaging said spring seat, an abutment member engaging the other end of said spring, a fixed support, and means pivotally connecting said abutment member to said fixed support.

8. A dump grate comprising, a middle section, and two side sections, said middle section consisting of an upper material supporting and feeding portion and a downwardly extending flange at each side of said supporting portion, each of said side sections also comprising an upper material supporting and feeding portion and a flange depending from each side of said upper portion, means for detachably securing said side sections to said middle section, an anti-friction roller disposed between the flanges of said middle section, and means extending through some of said flanges for supporting said roller.

9. A dump grate comprising, a middle section, and two side sections, said middle section consisting of an upper material supporting and feeding portion and a downwardly extending flange at each side of said supporting portion, each of said side sections also comprising an upper material supporting and feeding portion and a flange depending from each side of said upper portion, means for detachably securing said side sections to said middle section, an anti-friction roller disposed between the flanges

of said middle section, means extending through some of said flanges for supporting said roller and means for reciprocating said dump grate.

10. A dump grate comprising, a middle section and two side sections, said middle section consisting of an upper material supporting and feeding portion and a downwardly extending flange at each side of said supporting portion, each of said side sections also comprising an upper material supporting and feeding portion and a flange depending from each side of said upper

5 portions, means for detachably securing said side sections to said middle section, an anti-friction roller disposed between the flanges of said middle section, means extending through some of said flanges for supporting said roller, means for reciprocating said dump grate and a resilient support for said dump grate whereby the latter may move downwardly when subjected to abnormal loads, and means for reciprocating said 10 dump grate.

JOSEPH S. BENNETT.
